UNITED STATES PATENT OFFICE

2,452,288

BOWLING SCORE INDICATOR

Thomas R. Blando, Utica, N. Y.

Application October 2, 1945, Serial No. 619,746

1 Claim. (Cl. 177—384)

1
This invention relates to amusement devices and has for its object to provide means whereby bowling players' score is instantly indicated upon a score board at the players' end of the alley.

Another object of my invention is to provide a visible electric signal indicating instantly the number of pins knocked over by a bowler.

A further object of this invention is to provide an electric lighting system for bowling alleys for indicating each pin knocked down and the total score at the end of a three ball play.

Other features and advantages will become more readily apparent from the following description and the accompanying illustrative drawings in which:

Figure 1 is a diagrammatic view of my invention,

Figure 2 is an enlarged plan view of the pin seats,

Figure 3 is a diagrammatic sectional view on line 3—3 of Figure 2,

Figure 4 is a bottom plan view of a pin, and

Figure 5 is a wiring diagram.

In the accompanying drawings as above enumerated and in the following specification, like characters of reference indicate like parts throughout and in which, 10 indicates my invention diagrammatically; 11 is a section of a bowling alley; 12 is an electrically lighted score board at the outer end of the alley; 13, 14, 15, etc. indicate pin seats; 16 indicates a bowling pin, and 17 is a wall upon which is mounted an electric score indicator, 18.

In the end 19 of the alley 11 are embedded cup-shaped members 20, 21, 22, etc., pyramided in the usual manner and each cup terminates at its bottom 23 in a tubular neck 24, through which project the reduced ends 25 and 26, of spaced apart conductor posts 27 and 28, separated by insulation 29. The said cups 20, etc., are of insulating material such as rubber, plastic or the like. The insulator 29 is provided with a centrally disposed bore 30 through which slidably projects a normally raised switch pin 31, the upper end 32 of which extends above the surface of the pin seats 13, 14, etc., as located in the triangle 33. The lower end 34 of the pin 31 is pivoted to the switch arm 35 of a switch box 36. The two posts 27 and 28 extending into the box are adapted to be connected through action of switch lever arm 35, which arm is held outwardly in normally raised position by a spring within the box. A wire 39 connects post 27 with post 40 of the element 21. To post 41 of element 28 is connected by the end 42 of wire 43, connect-

2
ed with a lamp 44, on the indicator board 18. Wire 45 runs from the lamp to an electrical supply source, as does the wire 46 of post 38 of switch box 36. The hook up of all of the other pin seats 13, 14, etc., are identical as the hook up just outlined.

No bulb on the board 12 will become lighted, of course, if there is a break in the several circuits 46, 47, 48, etc., and normally there are 10 two such breaks at the pin seats 13, 14, 15, etc., and at the switch boxes 36, all of which are closed when the ten pins 16, 16', 16'', etc., are set up, due to the conductor plates 49, 50, etc., set in the recesses 51 of each of the said pins, which as 15 they are set up connect the posts 27 and 28, and at the same time push pin 31 will close the circuit to the switch on the posts 37 and 38, whereupon the lamps 44, 52, 53, etc., on board 12, will be lighted. This construction permits the pins 20 to be set in position while the circuit is broken to prevent arcing and the final downward movement of the pin 31 will operate the switch 36 to establish the circuit.

From the foregoing it will be seen that when 25 all of the pins are set up, all of the bulbs in the score indicator 12 will be lighted, but as each pin falls the lighting circuit of the pin is broken and its lamp extinguished, indicating instantly 30 the number of pins knocked down with each roll of a ball and the total number at the end of each play.

It is thought that persons skilled in the art 35 to which the invention relates will be able to obtain a clear understanding of the invention after considering the description in connection with the drawings. Therefore, a more lengthy description is regarded as unnecessary.

Changes in shape, size and rearrangement of 40 details and parts such as come within the purview of the invention claimed may be resorted to in actual practice if desired.

Having now described my invention that which 45 I claim as new and desire to procure by Letters Patent is:

In combination with a bowling alley, of a score 50 indicator therefor including a plurality of insulated sockets embedded in said alley, spaced semi-cylindrical contact members in each insulated socket, insulated sleeves disposed within said contact members, a switch adjacent each socket having a switch arm connected therewith pivotally supporting a switch pin for vertical and reciprocal movement through said sleeve, a signal box, electric lights therein of a similar number to the 55 number of said sockets, a source of electrical en-

ergy, wiring circuits and connections between said contacts, switch, lights and source of electrical energy, each circuit including in series the contact members of a socket, the corresponding switch and the corresponding lamp, and a plurality of contact plate supporting bowling pins adapted to seat on said spaced contact members to move said switch pin to close the switch adjacent the socket for completing the circuits to said lights for illuminating the same when said 10 bowling pins are in set position.

THOMAS R. BLANDO.
